UNITED STATES PATENT OFFICE.

WALTER J. MEILUK, OF HAMILTON, ONTARIO, CANADA, ASSIGNOR OF ONE-HALF TO
HENRY A. BUDROWSKI, OF HAMILTON, CANADA.

RECIPROCATING FLUID-MOTOR.

1,147,963.

Specification of Letters Patent. Patented July 27, 1915.

Application filed June 29, 1914. Serial No. 847,966.

To all whom it may concern:

Be it known that I, WALTER J. MEILUK, a subject of the Czar of Russia, residing at Hamilton, in the Province of Ontario and Dominion of Canada, have invented certain new and useful Improvements in Reciprocating Fluid-Motors, of which the following is a specification.

This invention relates to new and useful 10 improvements in a reciprocating fluid motor.

The primary object of the invention is the provision of a reciprocating motor adapted for actuation by any desired fluid and especially serviceable as a water motor and is 15 capable of continuous operation under a constant fluid pressure.

A further object of the invention is to provide a power imparting reciprocating 20 piston which is driven in alternating opposite directions by means of fluid pressure automatically governed for regulating its admission and exit to the piston chamber.

A still further object is to provide in connection with a fluid driven reciprocating 25 piston, an automatically operated oscillating valve and operating means for regulating the alternations of supply and exhaust of the motive fluid.

With these general objects in view and others that will appear as the nature of the 30 invention is better understood, the same consists in the novel combination and arrangement of parts hereinafter fully described, 35 illustrated in the accompanying drawings and pointed out in the appended claims.

In the drawings forming a part of this application and in which like designating characters refer to corresponding parts 40 throughout the several views, Figure 1 is a perspective view of the device. Fig. 2 is a top plan view thereof with one end of the piston broken away. Fig. 3 is a side elevation thereof. Fig. 4 is a top plan view with 45 a portion of the cylinder broken away and illustrating the piston in the reverse position from that shown in Fig. 2. Fig. 5 is a vertical transverse central sectional view of the device. Fig. 6 is a perspective view of 50 the fingered arm detached of the valve mechanism. Fig. 7 is a perspective view of the piston slide rod detached. Fig. 8 is a perspective view of the valve stem detached. Fig. 9 is a perspective view of the valve 55 plug detached. Fig. 10 is a central trans-

verse sectional view through the valve showing the valve port connecting between the fluid inlet and the piston pipe. Fig. 11 is a horizontal transverse sectional view thereof, and Fig. 12 is a horizontal sectional view 60 of the valve with the plug and its ports positioned opposite to that illustrated in Figs. 10 and 11.

Referring more in detail to the drawings, it is designed to mount the present construction of reciprocating motor upon a table or base 10. A hollow piston 11 has its opposite ends mounted for reciprocation within oppositely positioned cylinders 12, each having a piston chamber 13 therein and in 70 alignment with each other.

A valve cage 14 of cylindrical form is positioned at one side of the piston and is provided with a cap 15 while pipes 16 connect the opposite outer ends of the cylinders 12 75 with branch pipes 17, which latter pipes pass through the cage 14 and are tapped into the valve casing 18 arranged within the cage 14.

The valve casing 18 is provided with a 80 slightly tapered central bore 19 having an oscillating valve plug 20 mounted therein and adapted to be turned by means of the arm 21 which is secured to the top of the valve plug.

The fluid for operating the motor is conducted to the angular port 22 of the valve plug by pipe 23 upon the motor base 10, which pipe communicates through the pipe 24 beneath the base with the connecting 90 collar 25 within which the extension pipe 26 extends for rotation, said pipe 26 being carried by the valve plug and being in communication with the plug bore 22, as best illustrated in Fig. 10. A retaining plate 27 95 is secured to the lower surface of the turn plug and has a central opening 28 for the accommodation of the extension pipe 26, it being noted that with the valve plug positioned as illustrated in Figs. 10 and 11, the 100 inflowing fluid through the pipe 24 and collar 25 is admitted through the extension 26 to the bore 22 and from whence it passes through the left hand pipe 16 to the corresponding end chamber of the piston cylinder and may then operate upon the left end of the piston for forcing the same outwardly of the cylinder toward the right. In this position of the valve mechanism it will be seen also that the right hand pipe 16 allows 110

- the fluid to exhaust from the right hand cylinder 12 and to communicate with the right hand pipe 17 and thence to the right hand exhaust pipe 29 which is threaded into 5 one of the opposite openings 30 of the valve casing 18, such communication made possible by means of the adjacent positioning of one of the exhaust recesses 31 of the valve plug.
- 10 It will thus be seen with the valve positioned as shown in Fig. 11, the fluid will be admitted to the left hand piston cylinder chamber and will be exhausted from the right hand cylinder chamber while a reversing 15 of the position of the valve plug to that illustrated in Fig. 12 will exhaust the left hand chamber while simultaneously connecting the right hand chamber with the motive fluid supply.
- 15 The piston 11 is provided with a collar 32 having a connecting rod 33 which is adapted to be coupled up to any desired mechanism to be operated by the motor. A frame 34 is also carried by the piston collar 32 and 20 rigidly supports a rod 35 which reciprocates with the piston and is slidably journaled in the rearwardly projecting arms 36 of the valve cage 14.
- 25 An arm 37 is pivoted centrally to a strap 38 which traverses the cage 14 and has downwardly projecting spaced fingers 39 for freely receiving the arm 21 therebetween at the exterior of the cage 14, it being noted that the arm 21 projects through the front 30 slot 40 of the cage while the arm 37 projects through a similar slot 41 positioned thereabove in the front wall of the said cage.
- 35 A connection is provided between the rod 35 and the valve actuating arm 37 which 40 consists of a link 42 pivotally connected to the rod 35 substantially centrally thereof and having a coil spring 43 secured between the free end of said link and the actuating arm 37, the said link 42 entering the valve 45 cage through the rear slot 44.

The complete operation of the device it is thought will be apparent from the above detailed description thereof. The admission of fluid such as water is adapted to remain 50 under constant pressure in the supply pipe 24 which at all times communicates with the valve plug bore 22 and is adapted to be automatically connected with the opposite cylinder supply pipe 16 alternately by means 55 of the oscillating valve actuating means. It will be apparent that with the elements positioned as illustrated in Figs. 1 and 2, that the piston will be forced toward the right as the left hand chamber 13 is supplied with 60 the fluid under pressure and that the right hand chamber being in communication with the right hand exhaust pipe 30, the fluid 65 within said right hand chamber will be exhausted by the force of the incoming piston 70. Such movement of the piston carries

the rod 35 with its link 42 toward the right, which link having resilient connection with the arm 37, will be placed under increased tension until the link passes the center of the valve plug, above the same and whereupon the continued movement of the link toward the right will exert its force upon the arm 37 to force such arm toward the right to the position illustrated in Fig. 4, the operation being a forcible snapping of said 75 arm from one position to the other after the link has passed the line of center of the plug. It will be of course evident that the engagement of the fingers of the arm 37 with the arm 21 necessarily moves the arm 80 21 whenever the arm 37 is actuated and by all of which mechanism, the reciprocation of the rod 35 upon the movements of the piston automatically reverse the fluid valve for actuating the piston in its opposite reciprocations, it being also noted that the reversal 85 of the valve is not completely effected until each reciprocation of the piston is substantially completed. By all of this arrangement, there is provided a motor in which 90 any desired fluid may be supplied to the valve port extension 26 under a substantially uniform pressure and a continuous operation of the piston is thereby effected while the force of said piston may be utilized by 95 suitable connections with the rod 33.

While the forms of the invention herein shown and described are what are believed to be preferable embodiments thereof, it is nevertheless to be understood that minor 100 changes may be made in the form, proportion and details of construction without departing from the spirit and scope of the invention as set forth in the appended claims.

What I claim as new is:

1. A fluid motor comprising opposite cylinders in alignment with each other, a tubular piston mounted for reciprocation within said cylinders, a valve cage, a valve casing within said cage, pipes leading from the 110 opposite ends of said cylinders and passing through said cage and tapped into said casing, an oscillating valve within said casing adapted for automatically alternately connecting said pipes with a source of fluid 115 supply, and connecting means between the valve and piston.

2. A fluid motor comprising opposite cylinders in alignment with each other, a tubular piston mounted for reciprocation within 120 said cylinders, a valve cage, a valve casing within said cage, pipes leading from the opposite ends of said cylinders and passing through said cage and tapped into said casing, said casing provided with oppositely 125 positioned exhaust ports, an oscillating valve within said casing having oppositely positioned exhaust recesses therein, an angular fluid entrance port through said plug and having one end thereof adapted to com- 130

municate with said pipes and the other end of said port opening at the bottom of the plug, and means for oppositely positioning said plug.

5. 3. A fluid motor comprising opposite cylinders in alinement with each other, a tubular piston mounted for reciprocation within said cylinders, a valve cage, a valve casing within said cage, pipes leading from the opposite ends of said cylinders and passing through said cage and tapped into said casing, said casing provided with oppositely positioned exhaust ports, an oscillating valve within said casing having oppositely positioned exhaust recesses therein, an angular fluid entrance port through said plug and having one end thereof adapted to communicate with said pipes and the other end of said port opening at the bottom of the plug, a fluid inlet pipe, connections between said fluid inlet pipe and the lower end of said port, and means adapted for automatically shifting said plug with the port thereof alternately communicating with said pipes.

4. A fluid motor comprising opposite cylinders in alinement with each other, a tubular piston mounted for reciprocation within said cylinders, a valve cage, a valve casing within said cage, pipes leading from the opposite ends of said cylinders and passing through said cage and tapped into said casing, said casing provided with oppositely positioned exhaust ports, an oscillating valve within said casing having oppositely positioned exhaust recesses therein, an angular fluid entrance port through said plug and having one end thereof adapted to communicate with said pipes and the other end of said port opening at the bottom of the plug, a fluid inlet pipe, connections between said fluid inlet pipe and the lower end of said port, a rod rigidly secured to said piston, arm secured to said plug, a second arm pivoted to said cage and having a loose connection with the aforesaid arm, and resilient connecting means between a second named arm and rod.

5. A fluid motor comprising dual cylinders, a single tubular piston for said cylinders, a valve cage, a valve casing within said cage, an oscillating valve plug within said casing, means for effecting alternate communication between the ends of said cylinders and a source of fluid supply and fluid exhaust pipes, an arm upon said plug, a pivoted arm loosely connected with the aforesaid arm, a rod upon said piston, a link upon said rod adapted for traversing above said casing and a resilient connector between the free end of said link and said pivoted arm.

6. In combination with a fluid motor having a reciprocating piston rod, of a valve cage having two forward slots and one rear

slot therein, a valve casing within said cage, an oscillating valve plug within said casing, an arm fixed to said plug extending through one of said forward slots, an arm pivoted to said cage and extending through the other one of said forward slots and having downwardly projecting fingers positioned upon opposite sides of the aforesaid arm externally of said cage, a link upon said rod projecting through said rear slot and adapted for transverse movement above said casing and plug and a resilient connector between the free end of said link and said pivoted arm.

7. A device of the class described comprising a pair of oppositely disposed alined cylinders, a double piston reciprocating therein, a lug carried by said piston, a valve casing, an oscillating valve within said casing, an operating arm for the valve carried thereby, a second arm engaging the valve operating arm to shift the same, a spring connected at one end to said lug and at its other end to said second named arm, fluid supply means for the valve and communicating pipes between the valve casing and outer ends of each cylinder.

8. A device of the class described, comprising in combination with a cylinder and piston reciprocating therein, a valve cage, a valve within the casing, fluid supply means for the valve casing, means for supplying fluid from the valve casing to the cylinder, and operating connections between the piston and valve.

9. A device of the class described, comprising in combination with a pair of alined cylinders and a double piston rod reciprocating therein, a rod carried by said piston and movable therewith, a valve casing, a valve within the casing, pipes forming communication between the valve casing and cylinders, a pivoted arm operatively connected to said valve, and a flexible connection between said rod and arm whereby said valve is operated when the piston moves the arm.

10. A device of the class described, comprising a pair of cylinders, a double piston reciprocating therein, a valve cage, a rod carried by said piston adapted to be moved therewith and guided by said cage, a valve casing within said cage, a valve within the casing, fluid supply means for the casing, communicating means between the valve casing and outer ends of each cylinder, and operating connections between the piston and valve.

11. A device of the class described, comprising a valve cage, a pair of cylinders, a double piston operating in the cylinders, a rod carried by said piston and guided by said cage, a valve casing within the cage, a valve within the casing, fluid supply means extending between the valve casing and cyl-

inders, an arm fixed to said valve and movable therewith, there being a slot in the valve cage through which the arm extends, a second arm pivoted to the valve cage, a fork provided on the end of the pivoted arm and inclosing the aforesaid arm, a link pivoted at one end to said rod, a spring connected to the other end of said link and to the pivoted arm whereby the valve is moved by the spring when the arm supporting the link moves a sufficient distance to cause the spring to lie on either side of the valve arm.

12. A device of the class described, com-

prising a pair of cylinders, a piston reciprocating therein, a valve casing, a valve cage inclosing the casing, a valve within the casing, fluid supply means for the valve casing, pipes extending between the valve casing and the cylinders, and operating means for 20 the valve carried by the valve cage and piston.

In testimony whereof I affix my signature in presence of two witnesses.

WALTER J. MEILUK.
